Primary Examiner — Darlington Ly*Assistant Examiner* — Nasim Abdulaziz Ali(74) *Attorney, Agent, or Firm* — Amundsen Davis, LLC(57) **CLAIM**

The ornamental design for a vehicle wheel, as shown and described.

DESCRIPTION

FIG. 1 is a perspective view of a vehicle wheel embodying my new design; and,

FIG. 2 is a front elevation view thereof.

In the drawings the broken lines depict portions of the wheel that form no part of the claimed design.

1 Claim, 2 Drawing Sheets
